CLAIM

The ornamental design for a saddlebag tether, as shown.

DESCRIPTION

FIG. 1 shows a perspective view of an exemplary embodiment of saddlebag tether;

FIG. 2 shows a front view of the saddlebag tether of FIG. 1;

FIG. 3 shows a back view of the saddlebag tether of FIG. 1;

FIG. 4 shows a left view of the saddlebag tether of FIG. 1;

FIG. 5 shows a right view of the saddlebag tether of FIG. 1;

FIG. 6 shows a top view of the saddlebag tether of FIG. 1;

FIG. 7 shows a bottom view of the saddlebag tether of FIG. 1; and,

FIG. 8 shows a perspective view illustrating a pouch of the saddlebag tether of FIG. 1.

It may be appreciated that the drawings include dashed lines illustrative of stitching, and are not intended to show features that are excluded from the claimed design.

1 Claim, 8 Drawing Sheets
